Autoocrat Inc., Dayton, Ohio, a corporation of
Ohio

Application October 24, 1947, Serial No. 781,926

7 Claims. (Cl. 179—1)

1

This invention relates to signaling apparatus and more particularly to signaling apparatus for use in drive-in establishments such as theaters and the like.

This application is related to our copending application, Serial No. 74,802, filed February 5, 1949, which is a division hereof.

Drive-in establishments of various kinds have been in existence for many years and in more recent years, the drive-in theater has been added to the already long list of drive-in establishments. Car hops are usually used for giving service to patrons of all such establishments during their stay in the establishment. It is an object of this invention to provide a signaling system which eliminates the need for the car hops to disturb patrons who do not want service and to eliminate the need for patrons to use their horn or lights to signal for service.

Another object of this invention is to provide a signaling system which is not only applicable for use in drive-in establishments but also applicable for use in restaurant and any other type of establishment in which people gather.

In the usual drive-in theaters, it is customary to provide each automobile with a separate loud speaker which is connected to the main power amplifier which amplifies the signals picked up by the sound head of the projector. These speakers are fairly expensive and are frequently stolen or unintentionally pulled off from the mounting post by patrons who forget to remove the speaker from the car prior to leaving the parking space. It is an object of this invention to provide means for giving a signal when a speaker is disconnected from its support for any reason whatsoever.

Another object of this invention is to provide a signaling system for use in conjunction with either indoor or outdoor loud speakers in which the signaling is controlled by or from the loud speakers, or by or from component parts or attachments to the speakers.

Another object of this invention is to provide a lighting arrangement which may be used as a signaling medium, an advertising medium, or a medium of ornamentation.

Another object of this invention is to provide a signaling arrangement for use in a drive-in theater which eliminates the necessity for adding a large amount of extra wiring to take care of the signaling system.

2

Another object of this invention is to provide a signaling system which requires only a very small amount of current for its operation.

Another object of this invention is to provide an arrangement whereby patrons of a drive-in establishment may operate a signal visible from within a remotely located concession booth.

Another object of this invention is to provide a "concession" light which flickers when the light is turned on by a patron.

In the preferred circuit arrangement, the signal light flickers as the signal which operates the speaker varies and likewise the light intensity varies with the intensity of the signal. It is an object of this invention to make use of this phenomenon as a convenient means for warning the operator of a projection machine when the volume is too high.

Another object of this invention is to provide an arrangement for giving a signal in the event that the speaker cord becomes damaged.

Another object of this invention is to provide an arrangement whereby a single signal light is used for indicating either the removal of the speaker or the request for service by the car hop.

Still another object of this invention is to provide an improved mechanical construction of the various parts such as the speakers and the junction boxes which have been especially designed for use in the improved signaling system.

Other objects and advantages reside in the construction of parts, the combination thereof and the mode of operation, as will become more apparent from the following description.

In the drawings,

Figure 1 schematically shows a drive-in theater arrangement.

Figure 2 is a fragmentary elevational view showing the manner in which the loud speakers are mounted in relation to a junction box.

Figure 3 is a bottom view of a junction box.

Figure 4 is an end view of a junction box.

Figure 5 is a vertical sectional view showing the construction and arrangement of one of the speakers.

Figure 6 is a front elevational view of the speaker.

Figure 7 is a rear elevational view of the speaker.

Figure 8 is a side elevational view of the speaker.

Figure 9 is a plan view of the speaker.

Figure 10 shows a wiring diagram of the speaker circuit, and

Figure 11 is a wiring diagram showing the circuit used in a modified signaling system.

It has been chosen to illustrate our invention as applied to a drive-in theater, whereas many of the features of our invention are equally applicable to other types of installations.

Referring now to Figure 1 of the drawings wherein there is schematically shown the essential arrangement of a drive-in theater establishment, reference numeral 20 designates the screen used in conjunction with a sound projector 22. The projector is provided with a conventional sound head 24 which translates the impressions on the sound track of a sound film into electrical impulses which are first amplified in the pre-amplifier 26 and then further amplified in the main power amplifier 28. The amplifier 28 supplies power for operating individual speakers 38 which are plugged into sockets 52 on the junction boxes 30 which are placed at spaced points throughout the entire parking area generally designated by the reference numeral 32. In order to avoid unnecessary repetition, Figure 1 of the drawings shows only a fragmentary portion of the total parking area which would normally be used in conjunction with an outdoor theater.

It is customary practice in outdoor theaters to provide a concession booth such as the concession booth 34 shown in Figure 1 of the drawings. For purposes of illustration, the booth 34 has been shown behind the motion picture projector, whereas it is within the purview of the invention to locate the concession booth at any other convenient location. The operator of the concession booth employs car hops for going around to the occupants of the cars to take orders, to render service, to deliver orders, etc. in accordance with well known practice. Each car parked in the parking space 32 is provided with a speaker 38 on which a concession light operating switch 39 is provided which controls a light 56 mounted on the adjacent junction box 30 as will be explained more fully hereinafter.

The junction boxes 30 are removably mounted on suitable supporting posts 36 (see Figure 2) which are wired for sound and which serve to support a pair of speakers 38 at a convenient height so that they may be reached by the occupants of cars parked next to the junction boxes.

As best shown in Figures 2, 3 and 4 of the drawings, each junction box is provided with a pair of cross rods 40 arranged at opposite ends of the junction boxes for removably supporting the speakers 38. Each speaker is provided with a mounting hook or bracket 42 which is used for hooking the speakers on to one of the cross rods 40 or on to some portion of the car such as the car window 44 shown in Figure 2. A flexible cord 46 connects each speaker 38 to the power circuit within the adjacent junction box 30 in a manner to be explained more fully hereinafter.

Each junction box is provided with a depending socket element 47 which slips over the upper end of the mounting post 36 and is held in place by means of one or more set screws 48. Each speaker cord 46 is provided with a plug 50 which is adapted to cooperate with one of the two sockets 52 provided in the bottom wall of the junction box 30. These plugs 50 are preferably

held in place within the sockets by locking members 54 which are held in place in any suitable manner such as by screws which would be hard to remove without a screw driver. In this manner it becomes very difficult for anyone to remove one of the speakers without cutting or otherwise severing the cord 46. Each junction box is provided with a pair of signal means which for purposes of illustration, has been shown as a pair of neon lights 56 arranged in the manner indicated by the drawings. While there are certain advantages in using a neon light, any other type of light, a bell, horn or any other form of signal, depending upon the effect desired, could be used.

Referring now to Figures 5 through 9, it will be noted that each speaker element comprises a pair of cup shaped housing elements 60 and 62 which are provided with a lap joint 64 at their meeting edges as best shown in Figure 5. In order to make the joint waterproof and at the same time make it possible to separate the parts, a waterproof adhesive material 66 of the type soluble in gasoline or other well known solvents has been used between the overlying surfaces of the lap joint. One example of such a material is polyvinyl acetate. The front housing element 62 is provided with louver members 68 which are formed as integral parts of the housing member 62. A water impervious fibrous membrane or gasket 70 is provided directly behind the louvers and directly in front of the speaker element 72.

Directly above the louver members 68, there is provided a switch 74 connected in circuit with the neon light 56 in the manner indicated in Figure 10 of the drawings. While we have chosen to show a conventional toggle switch for controlling the apparatus of the signal light, it is obvious that any other type of circuit controller may be used in lieu of the toggle switch 74 without departing from the spirit of our invention. Directly beneath the louver 68 we have provided a volume control rheostat or potentiometer 76 which is connected in the circuit as shown in Figure 10 so as to make it possible to locally control the volume of the speaker.

As shown in Figure 10 of the drawings wherein we have shown a schematic circuit diagram illustrating the manner in which each speaker and signal light is connected to the main power amplifier, it will be noted that the individual speakers are connected to the main signal distribution lines 80 leading from the power amplifier 28 through a transformer 82. The transformer is located in the junction box 30 and includes a primary winding 84 and a secondary winding 86 connected in the circuit as shown in Figure 10. A separate neon light 56 is provided for each loud speaker unit and is arranged to be short circuited by closing of the switch 74 provided on the speaker. Each neon light 56 is connected between the one side of the secondary transformer coil 86 and the one side of the primary coil 84 and in series with a resistance 90 so that only a small amount of current flows through the neon bulb or through the short circuit which is controlled by the switch 74. An additional resistance 92 is connected in circuit 70 in the manner indicated in Figure 10 for further controlling the flow of current to the neon light 56. Neon lights having a $\frac{1}{25}$ watt rating have proven very satisfactory for this purpose. Whereas Figure 10 shows only the one junction box connected to the power lines 80, it is ap-

parent that a large number of junction boxes would all be connected to the one power amplifier 28. Likewise, Figure 10 shows only one speaker plugged in, whereas in actual practice one speaker would be plugged in to each of the sockets 52 provided on the junction box.

In the signaling system described hereinabove, the only signal given is that given by the light located directly on the junction box and this signal serves the multiple purpose of indicating to the car hops either that the occupants of a car want service or that someone has removed or disconnected the speaker from the junction box. As explained hereinabove, the intensity of the lights given is an indication to the projection operator as to the strength of the signal leaving the power amplifier 28 so that if the lights become unduly bright, it will be a signal to the operator to cut down the volume or if the lights become unduly dim, it will be a signal to the operator that the volume should be increased.

In Figure 11 of the drawings, I have shown a modified signaling arrangement for use when it is desired to operate a signal in the concession booth in addition to operating the signal on the junction box. The circuit diagram shown in Figure 11 is a fragmentary diagram intended merely for purposes of illustration and shows the signal lights for only four of the parking spaces in a given theater whereas, in actual practice there would be a given number of lights corresponding to the number of parking spaces. In the modification shown in Figure 11, the power for operating the signaling system is supplied from a transformer 100 which supplies power of suitable voltage and frequency for operating the entire signaling system. The out-put of the transformer 100 is connected to the lines 102 and 104 as shown. The line 104 is provided with a first branch line 106 which leads to a series of neon lights on a panel board 80a located within the concession stand 34 and a second branch line 108 which leads to the signal lights 110 mounted on the junction boxes in much the same manner as the signal lights described in connection with the preferred arrangement. Reference numeral 112 designates the signal lights located in the concession booth and reference numeral 114 designates the signal operating switch which would be mounted on the speaker in much the same manner that the switch 74 described hereinabove was mounted on the speaker. Thus, it will be noted that for each speaker, there is provided a pair of neon signal lights, one of which is located on the junction box and the other of which is mounted in the concession booth.

The wires leading from the neon lights 110 to the switches 114 are placed directly within the same cable which connects the individual speaker unit to the junction box so that severance of the speaker cable severs the wires which short circuit the lights 110. It will be noted that closing of the switch 114 not only short circuits the corresponding light 110 but also short circuits the corresponding light 112 which is arranged in parallel with the light 110. By virtue of this arrangement, opening one of the switches 114 or severing the cables leading to one of the switches 114 cause the adjacent signal lights 110 mounted on the junction box to light up and also cause the corresponding signal light 112 in the concession booth to light up.

In order to simplify this disclosure, the signaling system as shown in Figure 11 is separate from the loud speaker system whereas in actual prac-

tice one could use a common ground line for both systems and thereby eliminate unnecessary duplication of wires.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. In a drive-in theater, a power amplifier for amplifying audio signals, a transformer having a primary coil and a secondary coil, circuit means for connecting said primary coil to the output circuit of said power amplifier, a speaker, means for connecting said speaker to said secondary coil, an indicator means, a resistance element, means for supplying power from the output of said power amplifier to said indicator means and said resistance element in series including a first conductor connected to one side of said primary coil and to one side of said indicator means, and means including a resistance element connecting the other side of said primary coil to the other side of said indicator means, whereby voltage developed by said primary coil constitutes said means for supplying power.

2. In a drive-in theater, a power amplifier for amplifying audio signals, a transformer having a primary coil and a secondary coil, circuit means for connecting said primary coil to the output circuit of said power amplifier, a speaker, means for connecting said speaker to said secondary coil, an indicator means, a resistance element, means for supplying power from the output of said power amplifier to said indicator means and said resistance element in series including a first conductor connected to one side of said primary coil and to one side of said indicator means, and means connecting the other side of said primary coil to the other side of said indicator means whereby voltage developed by said primary coil constitutes said means for supplying power.

3. In a drive-in theater, a power amplifier for amplifying audio signals, a plurality of speaker stations each of which comprises a transformer having a primary coil and a secondary coil, circuit means for connecting said primary coil to the output circuit of said power amplifier, a plurality of speakers, means including a cable for connecting at least one speaker to each of said secondary coils, a neon light, a resistance element, means for supplying power from the output of said power amplifier to said neon light and said resistance element in series including a first lead wire connected to one side of said primary coil and to one side of said neon light, means including a resistance element connecting the other side of said primary coil to the other side of said neon light whereby voltage developed by said primary coil constitutes said means for supplying power, and means for short circuiting said neon light including conductor means forming a part of said cable whereby severance of said cable breaks said short circuit.

4. In a drive-in theater, a power amplifier for amplifying audio signals, a plurality of speaker stations, each of which comprises a transformer having a primary coil and a secondary coil, circuit means for connecting said primary coil to the output of said power amplifier, a plurality of speakers, means including cables for connecting

said speaker to each of said secondary coils, a separate neon light for each of said speakers, each of said neon lights having a resistance element connected in series therewith, means for supplying power from the output of said power amplifier to each of said neon lights including first lead wire means connected to one side of said primary coil and to one side of each of said neon lights, means including a resistance element connecting the other side of said primary coil to the other side of each of said neon lights whereby voltage developed by said primary coil constitutes said means for supplying power to said neon lights.

5. In a drive-in theater, a power amplifier for amplifying audio signals, a plurality of speaker stations, each of which comprises a transformer having a primary coil and a secondary coil, circuit means for connecting said primary coil to the output of said power amplifier, a plurality of speakers, means including cables for connecting said speakers to said secondary coil, a separate neon light for each of said speakers, each of said neon lights having a resistance element connected in series therewith, means for supplying power from the output of said power amplifier to each of said neon lights including first lead wire means connected to one side of said primary coil and to one side of each of said neon lights, means including a resistance element connecting the other side of said primary coil to the other side of each of said neon lights whereby voltage developed by said primary coil constitutes said means for supplying power to said neon lights, and means for selectively short circuiting said neon lights including conductor means forming a part of said cables whereby severance of any one of said cables breaks the short circuit for one of said neon lights whereby a signal is given.

6. In a drive-in theater, a power amplifier for amplifying audio signals, a transformer having a primary coil and a secondary coil, circuit means for connecting said primary coil to the output circuit of said power amplifier, a pair of speakers, means for connecting said speakers to said secondary coil, first indicator means, a first resistance element, means for supplying power from the output of said power amplifier to said first indicator means and said first resistance element in series including a first conductor connected to one side of said primary coil and to one side of said first indicator means, means including a resistance element connecting the other side of said primary coil to the other side of said first indicator means whereby voltage developed by said primary coil constitutes said means for supplying power, a second indicator means, a second resistance element, means for supplying power

from the output of said power amplifier to said second indicator means and said second resistance element in series including a conductor connected to said one side of said primary coil and to one side of said second indicator means, and means including a resistance element connecting said other side of said primary coil to the other side of said second indicator whereby voltage developed by said primary coil supplies power to said second named indicator means.

7. In combination, a power amplifier for amplifying audio signals, a transformer having a primary coil and a secondary coil, circuit means for connecting said primary coil to the output circuit of said power amplifier, a speaker, means for connecting said speaker to said secondary coil, an indicator means, a resistance element, means for supplying power from the output of said power amplifier to said indicator means and said resistance element in series including a first conductor connected to one side of said primary coil and to one side of said indicator means, and means connecting the other side of said primary coil to the other side of said indicator means whereby voltage developed by said primary coil constitutes said means for supplying power, and means including a manually operable switch for controlling the energization of said indicator means.
